INFANT'S GARMENT

Edward A. Sheridan, Pawtucket, R. I., assignor to
Vesta Underwear Company, a corporation of
Rhode Island

Application April 4, 1940, Serial No. 327,844

2 Claims. (Cl. 2—111)

My present invention relates to infants' garments and in particular aims to provide an improved and simplified construction for an infant's shirt, to eliminate centrally positioned buttons and other irritating reinforcement and supporting parts.

In the drawings, illustrating by way of an example an infant's shirt embodying my invention,

Fig. 1 is a front view of an infant's shirt, the front portion being shown buttoned to the back portion;

Fig. 2 is a view similar to Fig. 1, the front being unbuttoned and folded back;

Fig. 3 is a view similar to Fig. 2, the right portion of the garment being turned to disclose the complete absence of reinforcing tapes on the inner surface; and

Fig. 4 is a plan view of the blank for making the improved infant's garment.

Referring to Fig. 1, the infant's garment illustrated comprises a body portion 19 having a back 11 and a front 12, the back having a narrow forwardly extending support 13 to which the front may be buttoned. Two sleeve portions 14 and 15 are provided, if desired, the sleeve portions being secured by sewing to cut out portions of the blank as hereinafter described. The sides of the shirt are provided at the lower ends with reinforcements 16 of standard type for attaching diapers in the usual manner. All exposed edges of the garment are preferably finished as by elastic seaming 17.

As illustrated in Fig. 2, the back 11 has an arcuate neck cut out 18, and the front 12 has a deeper arcuate neck cut out 19, the support 13 being provided with a thin vertical tape 20 which has a plurality of buttons 21 secured thereto. The shoulder 23, formed by sewing as hereinafter described, also has one or more buttons 24 positioned or secured to the same. The front 12 has a reinforcement tape 25 sewed to the inside vertical edge thereof, and provided with a plurality of button-holes 26, and has a smaller reinforcing tape 27 secured to the inside upper edge thereof and provided with button-holes 28, the button-holes 28 being aligned with the buttons 24 and the button-holes 26 aligned with the buttons 21. It may be noted, referring to Fig. 3, that the tape 20 is secured to the support 13 by light stitching 29 so that no reinforcement tape or the like is positioned on the inner surface of the support.

The front 12, when folded over as illustrated in Fig. 1, has its button-hole tape 25 positioned

over the support 13, and the reinforcing tape 25 is thus prevented from engaging with the body of the infant, the reinforcement tape 27 similarly extending over the upper edge of the support, whereby no buttons, reinforcing tapes, or the like come in contact with the infant's body.

The improved infant's shirt thus has no irritating tapes, buttons, or other projections, and provides the infant with a complete chest coverage which cannot open or become unbuttoned so as to expose the infant's chest. Moreover, there is no tendency for the parts to spread or separate, as the buttons are all at one side, wherefore the pressure exerted by the infant's chest on the front of the shirt merely serves to more snugly fit the shirt to the infant, instead of separating the buttoned parts.

The novel construction also has the advantage that additional protection may be readily given to an infant's chest by providing a double front thickness without interfering with or inconveniencing the dressing or undressing of the infant. In practice, the novel shirt is found to possess substantial advantage, both in dressing and undressing, as the infant is placed on the back of the garment, and the front is then readily buttoned at the side.

The novel garment is more easily manufactured, and at a lower cost than standard central button garments, as a single blank of continuous material, such as illustrated at 30 in Fig. 4, completes the entire garment with the exception of the sleeve portions, the blank being readily cut from any desired textile material. The blank includes a body portion 31 having a narrow V shaped cut 32 at the upper portion at the right hand side and a second narrow V shape cut 33 positioned between the first cut and the left side of the blank, thus dividing the upper portion of the blank into three sections, the section 13a forming the support, the section 11a forming the back 11, and the section 12a forming the front 12, each of the sections being cut as indicated to provide shoulder tabs for the finished garment, it being found desirable to make the left hand shoulder tab 34 of the section 12a higher than the shoulder tab 35 of the section 13a, to thus provide additional length for preventing drawing or pulling of the garment at the right of the shirt when the parts are buttoned together as indicated in Fig. 1.

In completing the garment, the left section of the blank is folded over along the vertical dotted line 36, after the edges have been sewed and the reinforcing tapes have been secured thereto, the

right section 13a being folded and joined at the corresponding shoulder tab to the back shoulder tab. The narrow cuts 32 and 33 thus form the sleeve portions or sleeve cut outs, to which sleeves 15 may be sewed.

The novel shirt thus possesses manufacturing and assembly advantages that lower the cost of the finished articles, as there is very little waste of material; and the novel infant's shirt facilitates dressing and undressing of the infant, does not open or stretch or spread to expose the infant's chest, and hangs freely and fits snugly, thus resulting in a more desirable infant's garment.

Although I have described a specific constructional embodiment of the invention, it is obvious that changes may be made in the size and proportions of the parts, that the sleeves may be omitted or may be made full length as desired, that diaper reinforcing tapes may be positioned anywhere along the lower portion of the garment, or omitted if desired, and that various other changes in the securing means, such as the substitution of other securing means in place of buttons, may be made, without departing from the spirit and the scope of the invention as defined in the appended claims.

I claim:

1. An infant's garment of continuous material having three sections providing a front, an intermediate back, and a support, the back having an arcuate neck and shoulder tabs, the support being narrow and having a shoulder tab seamed to the adjacent back shoulder tab, and the front being of substantially the width of the back and having an arcuate neck and shoulder tabs, the front shoulder tab adjacent the back being seamed to the adjacent back shoulder tab, the support having a button tape on the upper face, and the front having a button-hole tape on the rear face adjacent the edge, the height of the front shoulder tab not seamed to the back shoulder tab being greater than the height of the support shoulder tab.

5 2. A blank for an infant's garment, comprising a rectangular portion of continuous material having two narrow vertical slits extending downwardly from the upper edge to provide three sections, the intermediate section having an arcuate neck portion and two shoulder tabs, one section being relatively narrow and having a shoulder tab, the third section being of substantially the width of the intermediate section and having an arcuate neck portion and two shoulder tabs, the height of the third section shoulder tab which is not adjacent the intermediate section being more than the height of the narrow section shoulder tab.
